UNITED STATES PATENT OFFICE.

JOHN W. KINCAID, OF COVINGTON, KENTUCKY.

MECHANICAL STOKER.

SPECIFICATION forming part of Letters Patent No. 761,685, dated June 7, 1904.

Application filed August 14, 1901. Serial No. 71,990. (No model.)

To all whom it may concern:

Be it known that I, JOHN W. KINCAID, a citizen of the United States of America, and a resident of Covington, in the county of Kenton and 5 State of Kentucky, have invented certain new and useful Improvements in Mechanical Stokers, of which the following is a specification.

The object of my invention is a mechanical 10 stoker which feeds coal into a furnace and disperses it to all parts thereof by means of blasts of steam.

In the accompanying drawings, in which like parts are indicated by similar reference- 15 letters wherever they occur throughout the various views, Figure 1 is a central longitudinal sectional view of a mechanical stoker embodying my invention, taken upon line xx of Fig. 2. Fig. 2 is a horizontal sectional view taken upon line yy , Fig. 1. Fig. 3 is an end elevation, the lower end of the rear journal-plate being broken off to expose the gearing in front of it. Fig. 4 is a vertical transverse sectional view taken upon line zz , Fig. 2. Fig. 5 is an inverted detail perspective view of the stem of the valve which controls the admission of steam into the steam-chamber. Fig. 6 is a detail perspective view of the valve.

Referring to the parts, A is an inclosed channel which is secured at one of its ends to door B of a furnace above the grate-bars and at the other end to a steam-chamber C, which has in its floor a port c , from which a channel c' leads into the bottom of channel A, which flares 35 outward from the point where it meets channel c' , as shown in Fig. 2, said flaring portion coming vertically below an opening f in a fuel-hopper F, which is situated above chamber C.

The opening and closing of port c is controlled by a flat rectangular slide-valve c^2 , having an opening c^3 in it of the size of port c and having four vertical flanges c^4 upon its sides.

The admission of steam into chamber C is controlled by a cylindrical piston c^5 , which reciprocates in a cylindrical chamber c^7 , which is formed in the walls of chamber C and which has horizontal channels c^8 cut into its walls. Channels c^8 run inward from the outer end of chamber c^7 , but end a distance from the 50 inner end thereof, so that when piston c^5 is in

its inward position it covers said channels and cuts off the admission of steam into the chamber until the piston returns to its outward position, uncovering the channels and again admitting steam into the chamber C. 55

Piston c^5 is secured to the end of a horizontal piston-rod c^9 , the opposite end of which terminates in a piston c^{10} , which reciprocates in a chamber c^{11} in the walls of chamber C. Piston-rod c^9 is bent downward to form a yoke 60 or frame c^{12} , which fits within flanges c^4 of slide-valve c^2 .

Journaled in the front and back walls of chamber C is a longitudinal shaft D, which has secured upon it a pinion d , which meshes with 65 a transverse worm E, to which a uniform rotation is imparted by two auxiliary steam-engines d' and d'' , the cylinders of which are secured to the exterior walls of chamber C.

Shaft D within chamber C carries a pinion d^3 , which has a series of cam-shaped teeth whose apices are upon the circumference of a circle and whose radial faces d^4 , d^5 , d^6 , and d^7 vary gradually in length from a maximum to a minimum. Pinion d^3 projects down into 75 yoke c^{12} , so that its teeth engage shoulder c^{13} . When in the rotation of pinion d^3 the apices are contacting shoulder c^{13} , opening c^3 in valve c^2 is carried to the left of port c , (see Fig. 4,) so that it is closed, and piston c^5 uncovers 80 channels c^8 , admitting steam to chamber C. When the apices pass the shoulder, the pressure of steam against the exterior face of piston c^5 carries it inward, shoulder c^{13} traveling along the radial face of one tooth to the base 85 of the next tooth of pinion d^3 , thereby closing channels c^8 , cutting off communication between chamber C and the locomotive-boiler and carrying valve c^2 to the right, so that opening c^3 uncovers port c an amount proportional to said radial face. The steam then rushes from chamber C out through port c 90 and channel c' , carrying the fuel from channel A into the furnace. The rapidity with which it carries the fuel forward and the point 95 in the furnace to which the fuel is thrown varies with the amounts port c is opened, which, as is seen, vary in direct proportion to the length of radial faces d^4 , d^5 , d^6 , and d^7 .

Hinged to the front end of chamber C is a 100

door c^4 , which hangs down over channel c' when port c is closed and when said port is opened is thrown up by the inrushing steam to cover opening f and prevent steam blowing into the hopper.

5 The valves which control the entrance of steam to engines d' and d^3 are reciprocated by rods $e e'$, which are coupled to opposite ends of the shaft of worm E by cams $e^2 e^3$.

10 Journaled in the ends of hopper F is a longitudinal spiral conveyer f' for feeding the coal toward the front end of the hopper. Upon its rear end shaft f^2 of said conveyer has a gear-wheel f^3 , which meshes with a 15 gear-wheel d^8 upon the rear end of shaft D. Since the frequency with which steam is allowed to pass from chamber C into channel A is controlled by the rate of rotation of shaft D and the rate of rotation of conveyer f can 20 be made to bear any proportion desired to that of shaft D by regulating the sizes of gear-wheels f^3 and d^8 , the amount of fuel deposited in channel A and the rate at which it is thrown into the furnace can be regulated to 25 any degree desired.

What I claim is—

1. In a mechanical stoker the combination of a steam-chamber, a channel leading thereto into a furnace above the grate-bars, a port in 30 the chamber for admitting steam into the channel, a valve for regulating the opening of the port, a hopper above the channel for feeding fuel into it, means for admitting steam into the chamber and means for intermittently 35 opening the valve to carry the fuel into the furnace substantially as shown and described.

2. In a mechanical stoker the combination of a steam-chamber, a channel leading from the chamber into a furnace, means for feeding 40 fuel into the channel, a valve for regulating communication between the channel and the steam-chamber, a valve for regulating the admission of steam to the steam-chamber and

means for operating the two valves whereby when one is opened the other is closed, substantially as shown and described. 45

3. In a mechanical stoker the combination of a channel leading into a furnace, means for feeding fuel into the channel, means for admitting intermittent blasts of steam into the 50 channel to carry the fuel into the furnace, and means for varying the strength of the successive blasts automatically, substantially as shown and described.

4. In a mechanical stoker the combination of a steam-chamber, a fuel-channel leading thence into a furnace, a steam-channel forming communication between the fuel-channel and the chamber, a flat valve to control the opening of the steam-channel, a piston-valve 60 in the walls of the steam-chamber to control the admission of steam thereto, a yoke for coupling the flat and the piston valves, a shaft journaled in the steam-chamber, a pinion thereon with teeth varying in shape and engaging the yoke 65 to open the steam-channel leading from the steam-chamber in varying amounts at the same time to operate the piston-valve to close off the admission of steam to the steam-chamber, and means for imparting a constant rotation to the 70 shaft, substantially as shown and described.

5. In a mechanical stoker the combination of a steam-chamber, a fuel-channel leading therefrom into a furnace, a hopper having an opening above the fuel-channel, a spiral conveyer for feeding fuel toward the opening in the hopper, a valve for controlling the passage of steam from the steam-chamber into the fuel-channel, a rotating shaft for operating the valve, means for rotating the shaft and means 80 for coupling the shaft and the spiral conveyer, substantially as shown and described. 75
